UNITED STATES PATENT OFFICE.

RICHARD L. POWELL, OF LEWISTOWN, PENNSYLVANIA.

SELF-CUSHIONING METAL TIE.

Application filed May 20, 1925. Serial No. 31,644.

To all whom it may concern:

Be it known that I, RICHARD L. POWELL, a citizen of the United States, residing at Lewistown, in the county of Mifflin and State of Pennsylvania, have invented a new and useful Self-Cushioning Metal Tie, of which the following is a specification.

The device forming the subject matter of this application is a railroad tie, and one object of the invention is to provide novel means whereby the tie will have the desired resiliency.

Another object of the invention is to provide novel means for connecting a rail to the tie.

It is within the province of the disclosure to improve generally and to enhance the utility of devices of that sort to which the invention appertains.

With the above and other objects in view which will appear as the description proceeds, the invention resides in the combination and arrangement of parts and in the details of construction hereinafter described and claimed; it being understood that changes in the precise embodiment of the invention herein disclosed, may be made within the scope of what is claimed, without departing from the spirit of the invention.

In the accompanying drawings:—

Figure 1 shows in top plan, a device constructed in accordance with the invention; Figure 2 is a longitudinal section; Figure 3 is a transverse section; Figure 4 is a plan of one of the rack bars; Figure 5 is a perspective view of one of the cushion plates; and Figure 6 is a fragmental section.

In carrying out the invention, there is provided a metal tie 1, which may be described, roughly and generally, as being of inverted trough-shape. The tie 1 comprises a top 2 and side walls 3 equipped at their lower edges with inwardly extended flanges 4. The top 2 of the tie has a trough-shaped longitudinal seat 5. In the base of the seat 5 there are key hole slots 6. An opening 7 is formed in the base of the seat 5 and is disposed between the key hole slots 6. In the side walls 3 of the tie 1 there are elongated openings 8. The openings 8 are enlarged at their ends, as shown at 9.

In the sides 3 of the tie 1 openings 10 are formed. The openings 10 are located, respectively, above and below the elongated openings or slots 8 and communicate therewith. In the openings 10 are located plates

11, the plates 11 having side flanges 12. The ends of the side flanges 12 engage the side walls 3 of the tie 1, within the tie. The plates 11 have end flanges 14 which engage the outer surfaces of the side walls 3 of the tie 1, the end flanges 14 having extensions 15. The flanges 14 and 12 of each plate project in opposite directions, and cooperate with the side walls 3 of the tie 1 to hold the plates 11 securely in place. Between the plates 11 is located a block 16 made of wood or other material, of a like sort. The flanges 12 on the plates 11 prevent the block 16 from moving lengthwise of the tie 1, as Figure 2 will make manifest. A securing element 17, such as a spike, is driven downwardly through the uppermost plate 11, into the block 16, to hold the block against shifting transversely of the tie. The opening 7 in the seat 5 of the tie 1 permits the driving of the securing element or spike 17.

A rack bar 18 fits closely in the seat 5 of the tie 1. The teeth of the racks on the bar 18 face in opposite directions, as shown at 19. The rack bar 18 has a depending projection 20. The projection 20 is received in the opening 7 of the tie 1. The projection 20 exercises two functions. First, it aids in preventing the rack bar 18 from shifting endwise. Second, it serves to hold down the securing element or spike 17. The rack bar 18 has key hole slots 21 which register with the key hole slots 6 on the tie 1. The rack bar 18 has depending fingers 22 which, engaging the tie 1 at the outer ends of the key hole slots 6, aid in preventing the rack bar 18 from moving endwise.

The rail 23 rests on the top 2 of the tie. Retainers 24 are supplied, and are adjustable in the seat 5 of the tie 1. The retainers 24 have racks 25 cooperating with the racks 19 of the rack bar 18. Securing devices 26, such as bolts, are adjustable in the registering key hole slots 6 and 21 of the tie and of the rack bar, respectively, the bolts 26 passing upwardly through the retainers 24. The head of each bolt 26 comprises a part 27 which fits in the restricted part of the key hole slots 6 of the tie 1, to hold the bolt 26 against rotation. The head of the bolt 26 includes, also, a laterally extended part 28, engaging the undersurface of the base of the seat 5, on each side of the restricted portion of the key hole slot 6. Nuts 29 are threaded on the upper ends of the bolts 26 and engage the retainers 24.

The tie forming the subject matter of this application is so constructed that it affords a simple but efficient means for holding the rail 23 in place, the tie having the necessary 5 resiliency and thereby avoiding one of the main objections to metal ties, namely, their extreme rigidity.

The tie forming the subject matter of this application may be alluded to properly as 10 a self-cushioning metal tie. Its construction is such that it will of necessity give a uniform cushion at all times, regardless of 15 traffic conditions. Especial attention is directed to the fact that practically all of the 20 fastening means are located well down in the trough-shaped seat 5, and, consequently, there is small chance that the mechanism alluded to will be broken or damaged by the 25 wheels of cars, or in any other way. Furthermore, when the track gets out of line, the rails may be moved, to secure alinement, with respect to the tie, it being unnecessary 30 to throw the tie, along with the rails, and move the tie on the ballast, after the ballast 35 has been tamped to a firm bed under the tie.

Having thus described the invention, what 36 is claimed is:—

1. In a device of the class described, a tie 40 provided with an opening, plates extended 30 transversely of the tie, a block located between the plates, a securing element mounted in one plate and engaging the block, the securing element being insertible through 35 the opening, a rack bar on the tie and having a projection received in the opening and located above the securing element, a rail 45 retainer cooperating with the rack bar, and means for holding the retainer in place.
2. In a device of the class described, a tie 50 provided in its top with an elongated

trough-shaped seat, a rack bar in the seat, means for connecting the rack bar to the tie to prevent the bar from shifting in the seat, a rail retainer extended into the seat and cooperating with the rack bar, and means 45 for holding the retainer in place.

3. In a device of the class described, a tie provided with elongated slots in its sides, plates extended between the sides of the tie, a cushion block located between the plates, 50 the slots extending on both sides of the cushion block, and means for holding a rail on the tie.

4. In a device of the class described, a tie provided in its top with a trough-shaped 55 seat, a rack bar located in the seat, the rack bar and the seat being provided with registering key hole slots, a retainer coacting with the rack bar, and a securing device 60 connected with the retainer, the securing device comprising a head engaged beneath the seat and insertible through the enlarged portion of the key hole slot, the retainer comprising a part fitting in the reduced portion 65 of the key hole slot of the seat to hold the securing devices against rotation.

5. In a device of the class described, a tie, a rack bar on the tie, the rack bar and the tie having registering key hole slots, the rack bar having means for engaging the tie 70 at the ends of the key hole slots of the tie to prevent the rack bar from shifting, a rail retainer cooperating with the rack bar, and a securing element adjustable longitudinally 75 in the key hole slot and connecting the retainer with the tie.

In testimony that I claim the foregoing as my own, I have hereto affixed my signature.

RICHARD L. POWELL.
